LOCOMOTIVE GRID SCREENING

Application filed July 13, 1927. Serial No. 205,414.

This invention relates to screening gases containing solid matter, and has for its object the limiting or restricting the size of solid matter which is permitted to pass 5 through the screening, and has for its further object to provide a screen which will permit of a certain amount of abrasion without increasing the size of the opening in the screening, and furthermore, to provide such a screening 10 in which the component parts have great strength to resist external stresses without distortion such as would increase the size of the screen openings and defeat the object of the screening. My device will stand up in 15 service a relatively long time, thus reducing the replacement cost and the time the locomotive is out of service during such replacement.

This invention relates particularly to coal 20 burning railway locomotives and especially to the screening used in the "front end" of such locomotives between the flues and the smoke stack to screen the gases of inflammable cinders and other material in fluid sus- 25 pension before they are thrown out of the smoke stack, thereby preventing hot cinders from causing fires along the right-of-way. These grid screens are positioned substantially 30 transverse to the direction of the flow of the gases.

It is customary to use a woven wire netting for such screening comprising interwoven wires normal to each other and my device is an improvement thereon and has for 35 its object a construction which increases the resistance of the screening to the physical destruction (abrasion) caused by the severe impact of the cinders and solid content in the gases, and has for its further object to increase the resistance of the screening to the 40 chemical action of the gases which destroy the screening.

These and other objects are obtained by the 45 specific and particular arrangement of the bars comprising the grid, which arrangement of bars produces the minimum retarding effect on the passage therethrough of fluids having solids in suspension with a maximum 50 total screen opening consistent with the kind of coal being burned for heating.

In the drawings:

Fig. 1 shows a typical front end of a railway locomotive with my device applied thereto.

Fig. 2 is a perspective view of my grid 55 screen.

Fig. 3 shows one of the grid bars.

Fig. 4 shows one of the other grid bars.

Fig. 5 shows one of the supporting bars.

Fig. 6 is a cross section of my grid. 60

Fig. 1 shows a typical front end of a locomotive and the usual parts, such as flues 1; front flue sheet 2; baffle plate 3; pivoted damper 4; exhaust nozzle 5; diaphragm plate 6; grid screen 7; smoke stack 8 and smoke 65 box barrel 9.

The gases and cinders emerge from the flues 1 and pass through the open damper 4 into chamber 11, while other gases and cinders emerge from the flues 10 into the chamber 11. All of these gases and cinders pass below the adjustable diaphragm plate 6 and thence through the screen 7 and out the smoke stack 8. 70

These gases attain a velocity of about 1800 75 feet per second, which causes a terrific impact between particles of cinders, etc., in the gases and the screening causing friction and consequent abrasion which wears out the wires comprising the woven netting. Therefore, in 80 my construction I replace the woven wire netting with a grid which comprises a series of substantially parallel grid bars spaced equidistance apart and positioned with the width of the bar parallel to the line of force of the moving gases so that this grid bar has great 85 strength to resist the bending forces caused by the moving gases and also will permit of considerable abrasion without increasing the size of the openings for the gases. Positioning these grid bars in the manner described also has the advantage that a considerable portion of them can be eaten away by the 90 chemical action of the gases without increasing the size of the opening for the gases. 95

By positioning the grid bars with their width parallel to the direction of the moving gases increases their strength as beams so that their supports may be placed further apart than in the case of a woven wire netting, 100

therefore, I position the supporting bars considerably further apart than the grid bars. Another object of the invention is to obtain a very strong grating to resist forces normal to it and at the same time to obtain a large total area of opening for the flow of gases and yet have a very small maximum width of opening. Bars may be positioned so as to form square instead of rectangular openings.

10 It may be advisable to form the supporting bars of thicker material than the grid bars which construction would require fewer supporting bars permitting them to be spaced further apart.

15 My improved construction comprises a plurality of spaced apart grid bars 29, 30, each having a thickness "T" which, for comparative purposes, are equal to the width "D" of the above mentioned wires and are spaced 20 apart distances "A" equal to the distance between the wires of the above mentioned netting. The supporting bars 31 are preferably spaced apart several times the distance between the grid bars and are preferably wider 25 than the grid bars. The upper grid bars 29, Fig. 4 are un-notched and have a top edge 29^a and a bottom edge 29^b. The lower grid bars 30, Fig. 3 have a top edge 30^a and a bottom edge 30^b and spaced notches 30' in the top 30 edge. The supporting bars 31, Fig. 5 have a top edge 31^a and bottom edge 31^b and upper spaced notches 31' in its top edge and spaced notches 31² in its bottom edge, these notches being arranged in staggered relation to each 35 other. The grid bars 29 are of a depth equal to the depth of the notches 31' and, therefore, when assembled with the notches, Fig. 2, the top edge 29^a of the grid bars 29 are level with the top edge 31^a of the supporting bars 31.

40 The notches 30' in the grid bars 30 and the notches 31² in the supporting bars are proportioned to permit the bars 30 when assembled in the supporting bars 31 to lie in a plane beneath the top edge of the grid bars 29 and 45 flush with the bottom edge 31^b of the supporting bars 31.

In other words, as shown in Figure 2, the grid screen comprises supporting bars having alternate grid bars 29 and 30 supported there- 50 in, the grid bars 29 being at a higher level than the supporting bars on one side of the grid and being at a lower level than the supporting bars on the other side of the grid, as shown by Figure 2 and in cross section by 55 Figure 6. In having the supporting bars 31 and the grid bars 30 notched as heretofore described, the grid is easily assembled and does away with the objectionable features in prior constructions wherein members are interwoven with each other or are connected to each other by means of enclosed openings or slots in the members. In assembling the grid screening, it is only necessary to place the supporting bars 31 in the proper position, 60 insert the grid bars 29 in the notches 31' and

then insert the notches 30' of the grid bars 30 in the notches 31² of the supporting bars 31 and to drive the bars into tight engagement with each other or to weld the grid bars to the supporting bars. After this assemblage 70 is completed it is only necessary to place the grid screen in its proper position in the smoke box, as shown by Figure 1, and an efficient screening of the solids is affected, as has been proven in a number of severe practical tests. 75 The grid bars and supporting bars are substantially rectangular but may be tapered and/or with rounded corners and each bar is positioned with its width "W", "Y" normal to the plane of the grating. The grid bars and supporting bars are secured together in any convenient manner such as by pressure or welding. The grid bars 30 are staggered relative to each other so as to provide an overlapping portion "C" or throat; that is, certain of 80 said bars are spaced below and between the other bars so that the adjacent bars have only a partially overlapped relation. In the construction illustrated the alternate bars are spaced below and between the bars there- 85 between.

When the gases pass through the netting or grid they are necessarily compressed which offers a certain amount of resistance and the smaller amount of time (or space) these gases 90 are held in compression the less resistance there is and lesser frictional abrasion of the grid bars. In the construction shown this compression space is only equal to the overlapping portion of the bars corresponding to "C". My construction has a further advantage; that it permits of considerable abrasion before the size of the opening is increased, whereas as soon as any wear occurs in the standard netting, the size of 100 the opening is immediately increased.

Exhaust steam from the engine cylinder is led to the nozzle 5 and then exhausted vertically through the smoke stack 8. As the piston nears the end of its stroke a port is opened 105 which permits the exhaust steam to escape through the nozzle 5 and out of the stack 8, thereby causing a partial vacuum at 12 which pulls the gases through the grating 7 and if this screening has restricted openings or offers resistance it acts as a choke to prevent the gases from coming out of the flue and in which event it becomes necessary to reduce the size 110 of the nozzle opening so as to obtain a sharper draft to cause a greater pull through the screening. This acts as a detriment on the force exerted in the cylinders by reason of the back pressure created thereby. In my construction I increase the total opening in 115 the screening, or decrease the resistance to a minimum, thereby reducing the resistance to the gases so that a sharp draft is not necessary. This means that the size of the nozzle 120 can be increased giving what is called an easy 125

exhaust which reduces the back pressure of the used steam in the cylinder.

In this application I have merely referred to the size of the opening in the woven wire netting or grid, it being understood that the size of the opening is contingent upon the kind of coal used, it being generally known, for instance, that lignite coal requires a much smaller maximum opening than bituminous coal.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. A spark arrester for locomotive smoke boxes, comprising a plurality of spaced apart supporting bars, a plurality of upper grid bars, a plurality of lower grid bars, the upper and lower grid bars being alternately positioned with adjacent grid bars having partially overlapping relationship and notched connections between the supporting bars and the grid bars.

2. A spark arrester for locomotive smoke boxes, comprising a plurality of spaced apart supporting bars having notches arranged in the top and bottom edges thereof in alternate relation to each other, a set of grid bars positioned within the upper notches and a second set of grid bars positioned in the lower notches, the adjacent grid bars having overlapping relationship.

3. A spark arrester for locomotive smoke boxes, comprising a plurality of spaced apart supporting bars having notches arranged in the top and bottom edges thereof in alternate relation to each other, a set of grid bars positioned within the upper notches and having their top edge substantially flush with the top edge of said supporting bars and a second set of grid bars having notches in the top edge thereof adapted to fit within the lower notches of the supporting bars and having their top edges below the top edges of the first mentioned set of grid bars.

4. A spark arrester for locomotive smoke boxes, comprising a plurality of spaced apart supporting bars having notches arranged in the top and bottom edges thereof in alternate relation to each other, a set of grid bars positioned within the upper notches and having their top edges substantially flush with the top edge of said supporting bars, and a second set of grid bars having notches in the top edge thereof adapted to fit within the lower notches of the supporting bars, the bottom edge of the first mentioned set of grid bars being positioned above the bottom edge of the said second series of grid bars.

5. A spark arrester for locomotive smoke

boxes, comprising a plurality of spaced apart substantially rectangular shaped supporting bars having notches arranged in the top and bottom edges thereof in alternate relation to each other, a set of substantially rectangular shaped grid bars supported within the upper notches and having their top edge substantially flush with the top edge of said supporting bars, and a second set of substantially rectangular shaped grid bars having notches in the top edge thereof adapted to fit within the lower notches of the supporting bars and having the top edge below the top edge of the first mentioned set of grid bars, the supporting bars being substantially normal to the grid bars.

In testimony whereof I affix my signature,
HARRY E. GILLETTE.
